STEAM SUPERHEATER

Frederick H. Einwaechter, Jr., Halethorpe, Md.,
and William N. Hedeman, Cincinnati, Ohio

Application October 24, 1940, Serial No. 362,630

2 Claims. (Cl. 122—462)

This invention relates to a steam superheater, particularly adapted for locomotive boilers, and may be designated as of a fire tube type; and preferably constitutes a plurality of longitudinal cylindrical shells in unit conduit connection horizontally projected into relative chambers located in the water space of the boiler.

The shells, each is interiorly subdivided by a longitudinal plate to provide a reverberatory course to obtain increase in length and establish the inlet and outlet connections therefor at one end of the shell, adapting the conduit connections therewith to be located within the smoke flue for more convenient access, facilitating installation and removal in making repairs. The divisions of the shells are traversed by longitudinal smoke or fire flues. In the employment of a plurality of superheater shells, the steam course or passages thereof are relatively interconnected, forming a series or single continuous circuit, with the inlet connection coupled to one shell and the outlet to a second.

A throttle valve is located in the smoke box adjacent the forward end of the boiler, and provides a header for the dry pipe and superheater at one side of the valve, and for the steam delivery conductors to the engine cylinders at an opposite side of the valve, increasing the efficiency facilitating installation, and the making of repairs.

An object of the invention is to provide a steam superheater composed of an elongated cylindrical shell for extension concentrically into an enlarged diameter fire tube or chamber in the water space of the boiler, and circumferentially spaced therefrom to form an annular passage for the hot gases emanating from the fire box, with the forward end of the shell projected into the smoke box adjacent the boiler and carrying the conduit fittings for making the steam connections with the dry pipe leading into the steam space of the boiler and throttle valve within the smoke box; the superheater interiorly providing parallel steam passages communicating at one end for a reverberatory course and longitudinally traversed by a plurality of small fire tubes for passing therethrough the hot gases in conjunction with the annular passage about the shell.

Another object of the invention is to provide a steam superheater unit of simple and compact construction for insertion into a fire tube space of a boiler, the unit including a plurality of parallel passages joined at one end and adapting a plurality of units to be connected in union for

effecting a zigzag course for the steam through the series.

Another object of the invention is to provide a steam superheater unit constituting an elongated cylindrical shell for insertion into a fire tube space of a boiler, and interiorly formed with a plurality of longitudinal passages joined in series with the inlet and outlet thereof located at a corresponding end of the shell for connection exterior of the boiler, and adapting a plurality of units to be directly connected and interchanged for effecting a continuous passage therethrough, the shell longitudinally traversed by a plurality of tubes for the passage of gases therethrough emanating from the fire box of the boiler.

Further objects and advantages of the invention will be more fully apparent from a description of the accompanying drawings, in which:

Figure 1 is a vertical section through the forward end of a locomotive and centrally through one of the superheater shells of the present invention.

Figure 2 is a section on line 2—2, Figure 1.

Figure 3 is a central section of a superheater shell and section of locomotive boiler, illustrating one form of water or superheater protecting wall at the rear end of the superheater shell to protect the same against direct exposure from the heat and flames in the fire box.

Figure 4 is a section similar to Figure 3 of a modified form of water wall.

The drawings disclose the invention, for the purpose of exemplification, as incorporated within a locomotive boiler. Therefore, a portion of a steam driven locomotive, insofar as is concerned herein, is conventionally illustrated, it however being recognized that the improvement is applicable to other types and classes of steam generating boilers for the superheating of the steam.

Referring to the drawings, 1 indicates the boiler barrel, 2 and 3 the front and rear flue sheet plates or boiler walls, traversed by a plurality of fire tubes 4 of the boiler. The tubes 4 at the rearward end communicate with the fire box or heating chamber 5, and at the forward end with the smoke box or chamber 6. The smoke box communicates with the smoke stack 7 and embodies the customary deflecting plate 9 about the intake end of the stack, which depends into the smoke stack. A steam conducting conduit 10, generally referred to as a dry pipe, extends longitudinally within the steam chamber 11 for the upper portion of the boiler. The intake of the dry pipe, following the general practice, is within the steam chamber 11, and in the present instance the

throttle valve 12, which connects with the dry pipe as a controlling outlet therefor, is located at the forward end of the dry pipe, exterior of the boiler and within the smoke box 6.

The dry pipe 10 at its forward end extends through the front flue sheet 2 of the boiler, with which it is externally in sealed connection and projects into the smoke box and is coupled to the body of the throttle valve 12. The valve body at one side of the valve is formed to serve as a manifold for making a valve controlled supply connection with a pair of conduits or steam lines 13, 13, respectively leading to steam cylinders at relative opposite sides of the locomotive with the upper portion of the conduits 13 disposed within the smoke box.

At the opposite side of the valve, the valve body provides a pair of branch or connecting passages 14, 15, one for connecting the dry pipe 10 with the intake of the superheater, and a second passage connecting the outlet of the superheater through the valve and manifold for steam delivery to the conductors 13, 13, leading to the several engine cylinders.

The valve body, with its valve and several branch passages, forms a very compact unit, materially simplifying and facilitating assembly and installation. The throttle valve body or casing projects through an opening in the top wall of the smoke box and carries a valve operating shaft 16 projecting laterally of the casing. A crank arm 17 is fixed on the outer end of the shaft 16, to which is attached an operating or pull rod extending to the cab.

The boiler within its water space has a pair of large diameter fire tubes 18, 18, adjointingly arranged in parallelism attached to the front and back flue sheets 2, 3, extending longitudinally through the water space, each providing a chamber for the reception of a superheater unit positioned concentrically therein. Each superheater unit consists of a cylindrical shell 19 provided with heads or ends 20, 21, secured thereto. Within the shell is a plurality of small diameter fire tubes 22 traversing the heads and welded or otherwise secured thereto. The shell is spaced from the chamber wall, thereby providing an annular passage for the hot gases emanating from the fire box, and hot gases from the fire box also passing through the small tubes 22 of the unit in their course to the smoke box. Spacer blocks 22a may be provided between the shell 18 and the chamber 19 at the bottom thereof to aid in sustaining the shell centrally of the chamber, and prevent any sagging contact of the shell upon the chamber.

Each superheater unit interiorly is subdivided by a diametrical partition plate 23, terminating a suitable distance from the rear end of the heater shell, providing alternately directioned passages as a rearward passage 24 and a forward passage 25 in communication at the rear end of the shell. The dividing plate 23 lies at an angle approximately forty-five degrees to the horizontal, and inclines upwardly toward the center of the boiler. The superheater units at their forward ends extend beyond the front flue sheet of the boiler into the smoke box. Connecting horizontal cross conduit fittings 26, 26, respectively are fixed to the adjacent inner sides of the projecting ends of the units, and relatively in union connection and combined to form a cross passage connecting the interior of the units below the diagonally disposed dividing plates. The fittings 26, therefore con-

nect the return or forward passage 25 of one unit with the rearward passage 24 of the second unit.

Each of the units at the forward free end and at the upper side of the shell is provided with a flanged conduit fitting 27 respectively connecting with the interior of the units above the diagonally disposed dividing plates, connecting the rearward directioned passage 24 of one unit with the dry pipe 10 through the branch passage 14 in the valve body 11, and the forward passage 25 of the second unit with the steam delivery conduits 13 through the branch passage 15 in the valve body controlled by the throttle valve. The passages 24 and 25 at relative opposite sides of the dividing plates of each unit, and when joined by the cross passage, establish a continuous zigzag course through the several units from the dry pipe to the throttle.

The conduit fittings 26, 27, of each unit are of duplicate construction and relatively disposed at right angles, rendering the units interchangeable within the heater chamber of the boiler, and when disposed in a vertical position provide an inlet and outlet for the units, and in a horizontal position a cross interconnecting passage for the units, all located at one and the same end of the heater shells, permitting all of the conduit connections to be made within the smoke box exteriorly of the boiler shell.

It is desirable to protect the rear end of the units within the heat chamber of the boiler from direct exposure of the heat and flame in the fire box by what is termed as a water or fire wall, of which several modifications are disclosed. In Figure 1, a superheater protecting wall is disclosed as composed of fire brick 28 disposed in a tier within the rear end of the shell 18 from the heater chamber within the boiler, with the brick of each layer spaced apart to provide ducts or openings through the wall and located staggered from the ducts in the next adjoining layer of brick, the openings having a greater area than that of the tubes 22 through the superheater.

In Figure 3, the shell 18 has an annular row of apertures 29 therethrough and interiorly carries a pair of spaced circumferentially flanged discs 30, 30, arranged at opposite sides of the apertures to form a water space 31 traversed by a plurality of tubes 32 secured to the discs. In Figure 4, the shell 18 has a closed inner or rear end which lies wholly within the water space of the boiler and is spaced from the rear flue sheet of the boiler traversed by a plurality of tube sections 33 secured to the boiler wall and the head or end of the shell 18.

Having described our invention, we claim:

1. In a boiler of the locomotive type, a plurality of steam superheater units, each composed of an elongated cylindrical shell for insertion into a tube extending through the water space of the boiler for emitting gases from the fire chamber at the rear end to a smoke chamber at the forward end of the boiler, the forward end of the shell projecting into a smoke chamber, the shell internally having a reverting passage with inlet and outlet connections therefor at the forward end of the shell for making conduit connections within the smoke chamber, the connections for each shell having their axes at right angles and their outer ends spaced equidistant from the axis of a respective shell for interchangeably positioning the shells, adapting the same to be horizontally interconnected, and to provide for an inlet and outlet connection perpendicular to the interconnection of the shells.

2. In a boiler of the locomotive type, a plurality of steam superheater units, each composed of an elongated cylindrical shell for insertion into a tube extending through the water space of the boiler for emitting gases from the fire chamber at one rear end to a smoke chamber at an opposite end of the boiler, the shell circumferentially spaced from said gas emitting tube and having a plurality of gas emitting tubes longitudinally traversing the same, the shell internally having a reverting passage with inlet and outlet connections at a corresponding end of the shell, the reverting passages of the units in conduit connection for a continuity thereof, the inlet and outlet connections for each shell having their axes rela-

tively at right angles and their outer ends spaced equidistant from the axis of a respective shell for interchangeably positioning the shells, and adapting the same to be horizontally interconnected, and providing for a second connection perpendicular thereto, and a header for said units providing independent branch passages, one for connecting the inlet to the superheater unit with a dry pipe leading into the steam space of the boiler, and a second branch passage for connecting the outlet of the superheater unit with a valve chamber in the header and including a throttle valve for the steam delivery control.

FREDERICK H. EINWAECHTER, JR.
